UNITED STATES PATENT OFFICE.

JOHN PHELPS, OF LA PORTE, INDIANA.

IMPROVED WASHING-MACHINE.

Specification forming part of Letters Patent No. 35,037, dated April 22, 1862.

To all whom it may concern:

Be it known that I, JOHN PHELPS, of La Porte, in the county of La Porte and State of Indiana, have invented a new and Improved Clothes-Washing Machine; and I do hereby declare that the following is a full, clear, and exact description of the same, reference being had to the accompanying drawings, making a part of this specification, in which—

Figure 1 is a longitudinal vertical section of my invention, taken in the line *x x*, Fig. 2. Fig. 2 is a transverse vertical section of the same, taken in the line *y y*, Fig. 1.

Similar letters of reference indicate corresponding parts in the two figures.

This invention relates to an improved clothes-washing machine of that class in which a reciprocating partially-rotating rubber is used in connection with a concave.

The object of the within-described invention is to obtain a simple and efficient means for regulating the pressure of the rubber on the clothes; and to this end the invention consists in having the bearings of the rubber shaft attached to a sliding frame which has an adjustable weight and elastic bar connected with it and arranged as hereinafter fully shown and described.

To enable those skilled in the art to fully understand and construct my invention, I will proceed to describe it.

A represents a framing, which may be constructed in any suitable way, to support a box, *B*, which is of **V** form in its transverse section and has a concave, *C*, fitted within it, said concave having its lower part, *a*, about of circular form and its upper part at each end of slightly convex form, as shown at *b b*. This concave *C* is corrugated transversely, as shown at *c*, and it has side pieces or cleats, *d d*, attached to its under side, which bear or rest on the sides of the box *B* and admit of a space, *e*, between the concave and box. At the upper part of the concave, at each end, there is made an opening, *f*, to admit of the suds passing down into space *e* should any reach the top of the concave.

D is a semi-cylindrical rubber which is attached to a shaft, *E*. This convex has its face or outer surface corrugated longitudinally, as shown at *g*, said corrugations being parallel with the corrugations *c* of the concave. The rubber *D* is directly over the

lower circular part, *a*, of the concave, as shown in Fig. 1.

The shaft *E* of the rubber *D* is fitted in bearings *h h*, which are at the upper end of a sliding frame, *F*. This frame *F* is composed of two side strips, *i i*, which are fitted between guides *j j* at each side of the box *B*, the lower ends of said strips underneath box *B* being connected by a cross-tie, *G*.

H is a spring one end of which is permanently attached to a cross-bar, *k*, in the framing *A*, and the opposite end fitted in the center of the cross-tie *G*. This spring *H* has a sliding or adjustable weight, *I*, placed on it.

The shaft *E* of the rubber *D* has handles *J* attached to its ends. The spring *H* has a tendency to keep the rubber *D* elevated above the surface of the concave, so that it shall not be in contact therewith. The rubber *D* is operated, through the medium of the handles *J*, with an oscillating movement, the clothes being acted upon or subjected to the necessary friction and rubbing between the concave and rubber. The weight *I* gradually increases the pressure of the rubber on the clothes by being adjusted on the spring *H* nearer to or farther from the lower part of the frame *F*. When the weight *I* is adjusted on the spring *H* back from the frame *F*, it of course has less power on the frame *F*, and the pressure of the rubber *D* on the clothes is reduced, the pressure of the latter being increased as the weight is shoved toward the frame. By this arrangement the pressure of the rubber *D* may be graduated as desired with the greatest facility, and the machine thereby rendered capable of being adapted for washing fine or coarse clothes.

I do not claim a reciprocating partially-rotating rubber in connection with a concave for washing clothes, for these parts constitute an old and well-known device; but

What I do claim as new, and desire to secure by Letters Patent, is—

The reciprocating partially-rotating rubber *D* and the concave *C*, in combination with the spring *H*, adjustable weight *I*, and sliding frame *F*, all arranged for joint operation, as and for the purpose herein set forth.

JOHN PHELPS.
